UNITED STATES PATENT OFFICE.

GEORGE L. McCALLUM, OF NEWERF, PENNSYLVANIA.

DEVICE FOR CHANGING THE ANGLE OF BLADES OF PROPELLERS.

SPECIFICATION forming part of Letters Patent No. 734,468, dated July 21, 1903.

Application filed September 23, 1902. Serial No. 124,510. (No model.)

To all whom it may concern:

Be it known that I, GEORGE L. McCALLUM, a citizen of the United States, residing at Newerf, in the county of McKean and State of Pennsylvania, have invented new and useful Improvements in Devices for Changing the Angle of the Blades of a Propeller for Reversing the Direction of the Vessel, of which the following is a specification.

My invention relates to improvements in a device for changing the angle of the blades of a propeller for reversing the direction of the vessel.

The object of my invention is to provide a propeller-wheel in which the blades are so arranged that they can be moved at different angles in order to change the direction of the vessel from forward to a backward movement without reversing the engine, or vice versa.

Another object of my invention is to provide a device in which the blades of the mechanism for operating said blades is locked in the desired position and said locking mechanism operated by the blades-operating mechanism.

A further object of my invention is to provide a device of this character which will more effectively accomplish the above results and one which is more simple and cheap in its construction.

In the accompanying drawings, Figure 1 is a longitudinal sectional view. Fig. 2 is a transverse sectional view taken on line $x-x$, Fig. 1. Fig. 3 is a transverse sectional view taken on line $y-y$, Fig. 1. Fig. 4 is a transverse sectional view taken on line $z-z$, Fig. 1. Fig. 5 is an enlarged sectional view of the propeller. Fig. 6 is a transverse sectional view of the propeller. Fig. 7 is a sectional view showing the blades in the reverse position to Fig. 5. Fig. 8 is a side view of the propeller. Fig. 9 is an enlarged sectional view of the pistons removed. Fig. 10 is an enlarged sectional view of the packing-rings, showing the means of connecting the steam-supply pipe. Fig. 11 is a plan view of my device, showing the steam supply and exhaust pipe and valves and the mechanism operating the same.

Referring now to the drawings, A represents a cylinder, which is preferably of an elongated form and is provided throughout its entire

length with the central bore A' , and at its extreme outer ends the said bore is slightly enlarged at a for the reception of a packing a' , which will be hereinafter more fully described, the ends of said cylinder being provided with outwardly-extending annular flanges B and B' . The forward flange B is bolted to a disk-shaped member C , which is provided with an outwardly-extending elongated cylindrical member C' , which is mounted in a bearing carried by the vessel and by means of which the whole cylinder is adapted to revolve. Secured to the outer end of said member is a crank C^2 , which is adapted to rotate said member, and said crank is connected to the engine in any desired manner, as this forms no part of my invention. The said disk-shaped member C is provided with a reduced recess c , which is adapted to receive the piston-rod carried by the piston, as will be hereinafter more fully described, and surrounding said outer end of said recess is an enlarged packing-receiving opening C^3 , which is adapted to receive a portion of the packing a' , and thus completely and effectively close the end of the cylinder. The opposite end of the cylinder is closed in precisely the same manner, and the cylindrical member D is also mounted in bearings like that at the opposite end, and thus it will be readily seen that the whole cylinder and working mechanism carried thereby are mounted in a horizontal position and adapted to revolve.

Centrally located within the cylinder is a piston E , which is provided with two longitudinally-extending openings e and e' , through which pass the bolts F and F' . Carried by the opposite ends of said bolts and rigidly secured thereto by means of screw-threads carried by the bolts are two pistons G and G' , located adjacent opposite ends of the cylinder and adapted to freely slide therein, while the bolts carried thereby pass loosely through the central piston, and it remains in its stationary position. The ends of the pistons G and G' carry packing g and g' , which is to insure a perfectly air-tight cylinder.

Passing through the entire length of the cylinder and through all three of the pistons is a piston-rod H , which is rigidly connected to the two outer pistons G and G' in any de-

sired manner, and the forward end of said piston-rod H extends through the packing a' and out into the recess c, carried by the cylindrical member C', and is adapted to freely 5 reciprocate therein, the purpose of which is to allow it to move back and forth, yet it is at all times within said member for the purpose of strengthening the device. The rear end of said piston-rod H extends through the 10 rear end of the cylinder member D and out through the outer end, the purpose of which I will now proceed to describe.

The cylindrical member D carries an enlarged portion I, which is provided with a 15 socket D', and fitting within said socket is the propeller-carrying member D². Said member is held in said socket by bolts d and keys d², and thus it is removably held therein. The shaft H passes all the way through this 20 member, and the outer end of said member D² is provided with any desired number of flat surfaces I', and carried by each surface is an outwardly-extending rounded stud i, which is provided at its outer end with a circumferential groove i', and rotatably mounted 25 upon each stud is a blade J, which is constructed like the ordinary propeller-blade, and passing through said blades and resting within the grooves i' are screw-threaded bolts 30 j, which firmly lock the blades on the studs, yet they are not held against rotation. The said flat surface is provided with a cut-away portion I², the purpose of which I will now proceed to describe. The outer end of 35 the piston-rod H passes through the enlarged portion I and extends considerably beyond, and rigidly secured to the outer end h thereof is a block K, which is provided with the same number of flat surfaces as the portions 40 k, and resting within the said recesses k and having its opposite end resting within the recess I², carried by the member I, are the links I³, and it is understood that there is to be a recess for each flat surface on each member 45 and a blade for each flat surface. The said links are connected to the member K by a screw-threaded bolt K, but is allowed to turn freely thereon, and the opposite ends of the links rest within the recesses in the member 50 I, and passing through the shank of the blades and screw-threaded therein are bolts L, which have their inner ends l passing through the ends of the links, and thus you will see that by the moving in or out of the 55 piston H the block K is moved and the link I will cause a partial rotation of the blades, and thus it will be seen that the vessel will have a backward instead of a forward movement. In order to prevent the twisting and 60 turning of the block K under the great strain it is put under, I provide the member I with the outwardly-extending bolts l', which pass freely through the member K, but are of a length to be wholly within the block K at all 65 times, and thus it is firmly held against twisting or any lateral strain.

The member I has an opening K² in its outer face, and fitting within said opening is an outwardly-extending collapsible packing T, which surrounds the piston-rod H and is secured to the block K. When the piston is drawn in and the block K is brought against the member I, the packing is within the opening K². 70

The cylinder A is provided with steam-supply rings N adjacent each end, and these rings rest in annular grooves. These rings N consist of circular members completely surrounding the cylinder and rotatably mounted thereon and having an inner annular packing-groove n, which is adapted to receive the packing n', and having an annular steam-chamber n². The cylinder opposite said chamber n² is provided with openings n³, whereby steam is admitted to the cylinder and the piston is caused to move therein. It is understood that there is one of these rings at each end, and said rings are held stationary in any desired manner while the cylinder is rotating, thus causing the rotation 85 of the propeller when rotated by the engine. Each of said steam-rings N is provided with an opening N⁴, and passing within said opening is the steam-supply pipe N², and carried by said pipe is a washer N⁵, which bears 90 against the outside of said ring and the extreme outer end of the reduced portion N⁴, which is screw-threaded and a nut N⁶ screwed thereon, whereby the pipe is firmly secured to the ring. The said pipe N² extends laterally 95 from the said ring and is then bent at right angles to said laterally-extending portion and is provided with an elongated portion 1, extending parallel with the cylinder, and is connected to the boiler or the source of steam-supply in any desired manner. The outer 100 end of said laterally-extending member N² is provided with a valve 2 and intermediate said valve and ring is an exhaust-pipe 3, which extends at right angles to said pipe 105 N² and carries a valve 4 adjacent thereto. The valve 2 carries an outwardly-extending rigid member 5, to which is pivoted the lever 6, and connected intermediate the ends of 110 said lever is the valve-stem 7 of the valve. 115 Connected to the rear end of the valve 2 is an arm 8, which is connected to the lever 6 by a coil-spring 9, the tendency of said spring being to draw the lever inward, and thus force the valve-stem in and normally close the 120 valve and prevent the steam from passing into the ring. The valve 4 is constructed in precisely the same manner as the valve 2; but the spring 9' forces the lever outward, and thus the normal position is open. The pipes 125 N² and 3 carry the frame 10, to which are rotatably mounted the pulleys 11 and 12, and the outer end of the exhaust-valve lever 6 also carries a pulley 13.

A rope or cable 14, extending from any desired point of the vessel, extends over the pulley 12 and around the pulley 13 and up 130

over the pulley 12 and is made fast to the outer end of the valve supply-lever 6, and it will be readily seen that by pulling the rope or cable 14 the valve 2 is opened and 5 steam passes into the ring and at the same time the valve 4 is closed, and thus steam is admitted to the rear end of the cylinder.

Connected to the pipe 1 is a pipe 15, which extends to the steam-ring N at the opposite 10 end of the cylinder. Said pipe also has a valve, and the laterally-extending exhaust-pipe 16 below is provided with a valve. The valves and mechanism are arranged in precisely the same manner as before described. 15 It will be clearly seen that the normal position of the valves when both cables are released is such that steam is not admitted to either end of the cylinder and the exhaust-valves are open; but by pulling one cable the 20 steam is admitted to the one end and by pulling the other cable steam is admitted to the opposite end. Thus it will be clearly seen that the piston is forced from one end of the cylinder to the opposite end, and the piston-rod 25 carried thereby moves the propeller-blades and causes them to partially rotate, as heretofore described.

In order to lock the propeller in the desired position, so that the vessel is either going forward or backward and not to rely wholly upon the steam-pressure for the same, I provide a central member O, completely surrounding the cylinder, and carried by said central member is a key O', which passes through the 30 elongated slots o in opposite sides of the cylinder and through the central piston E and the piston-rod H. The said member O, it will be clearly seen, slides on the cylinder, and as the piston-rod is moved it is in turn 35 moved through the key O'. Rigidly connected to the ends of the cylinder, just inside of the steam-rings N, are the outwardly-extending circumferential flanges o², and carried by said flanges are longitudinally-extending 40 guiding-bolts P, which pass through the central movable member O and carry coil-springs p on each side thereof, which normally hold 45 said central member centrally between the flanges O². The outer ends of said central 50 member are provided with lugs Q, which are arranged in pairs, and the inner ends of the flanges O² are also provided with the lugs Q', and pivoted between said lugs and the lugs Q on the central member are toggle connections R, and the lugs Q carry a spring r, which 55 normally rests upon the toggle connection and holds it down or has a tendency to hold said connection in a downward position beyond the center. It will be clearly seen that 60 after the center pivotal point has passed the center it cannot be released by any pressure due to the forcing together of the two members to which said toggle is connected.

In order to force said toggle upward after 65 it has passed the center, I provide what I term as "unlockers" S, which rest upon the

cylinder and have a beveled portion s, and said unlockers are adapted to slide within the openings o in the members O and O², and carried by the inner end of said unlockers are 70 keys s, which pass through the cylinder and into the piston, and thus it will be seen that when the device is in the position shown in Fig. 1 when pressure is admitted to the forward end of the cylinder the piston moves, 75 and thus moves the keys s, which in turn move the unlockers, and the beveled portion engages the hinge or toggle connection and forces it upward past the center, and as the piston is continued to be moved the key O' 80 moves the member O outward, and thus brings the toggles carried by the opposite end in a downward position and is held in said position until steam is admitted to the opposite end of the cylinder, and the operation is the 85 same, and thus the propeller-blades are locked in either of the two positions, so that the vessel will travel either forward or backward.

The operation of my device is as follows: When the blades and the mechanism are in 90 the position shown in Fig. 1, the vessel is traveling forward through the rotation of the whole mechanism, which is operated by an engine, and when it is desired to reverse the movement of the vessel steam is admitted to 95 the opposite end of the cylinder, which moves the piston, and the piston in turn moves the unlockers under the toggle-joints which raises them. As the piston continues to travel the blades are thrown in a different 100 angle, as heretofore described, and the toggles are drawn downward and locked in a manner before described, and the movement of the vessel is reversed. When it is desired to stop the vessel, the engine itself is stopped. 105

Having thus described my invention, what I claim, and desire to secure by Letters Patent, is—

1. A mechanism of the character described, comprising a propeller composed of adjustable blades, a rotatable cylinder carrying said propeller, a piston within said cylinder and a mechanism operated by said piston for adjusting said blades, substantially as described. 110

2. A mechanism of the character described, comprising a propeller composed of adjustable blades, a rotatable cylinder carrying said propeller, a piston within said cylinder, a piston-rod carried by said piston and means carried by said piston-rod for adjusting said 115 blades, substantially as described.

3. A mechanism of the character described, comprising a propeller composed of adjustable blades, a rotatable cylinder carrying said propeller, a piston within said cylinder, a piston-rod carried by said piston, and a pivoted 120 connection between said piston-rod and said blades, substantially as described.

4. A mechanism of the character described, comprising a propeller composed of adjustable blades, a rotatable cylinder carrying said propeller, a piston within said cylinder, a pis- 125

ton-rod carried by said piston and links connecting the outer end of said piston-rod and the adjustable blades, substantially as described.

5. A mechanism of the character described, comprising a propeller composed of adjustable blades, a rotatable cylinder carrying said propeller, a piston within said cylinder, a piston-rod carried by said piston, links connecting the outer end of said piston-rod to the adjustable blades, and a mechanism for holding said piston in either end of the cylinder, substantially as described.

6. A mechanism of the character described comprising a propeller, composed of adjustable blades, a rotatable cylinder carrying said propeller, a piston within said cylinder, a piston-rod carried by the piston, and links having one end connected to the said piston-rod and their opposite ends pivoted to the blades, substantially as described.

7. A mechanism of the character described, comprising a rotating cylinder, outwardly-extending members carried by said cylinder and rotating therewith, laterally-extending studs carried by said member, propeller-blades loosely mounted on said studs, a piston within said cylinder, a piston-rod carried by said piston, a block carried by the outer end of said piston-rod, and links pivoted to said block and the adjustable blades, substantially as described.

8. A device of the character described, comprising a rotatable cylinder, an outwardly-extending member carried therewith, outwardly-extending studs carried by said member, blades adapted to be adjusted on said studs, the said member, having cut-away portions adjacent the shank of the blades, a piston within the cylinder, a piston-rod carried by said piston, a block carried by said piston-rod, and links pivoted to said block and resting within the recess in the member, and pivoted to the adjustable blades, substantially as described.

9. A device of the character described comprising a rotating cylinder, a propeller-wheel carried therewith, and composed of adjustable blades, a piston within the cylinder, a piston-rod carried by the piston, means operated by the piston-rod for adjusting said blades, and means for locking the piston at either end of the cylinder, substantially as described.

55. 10. A device of the character described comprising a rotating cylinder, a propeller carried therewith and composed of adjustable blades, a piston within the cylinder, a piston-rod carried by the piston, a means carried by the piston-rod for adjusting said blades, an outwardly-extending member carried by the piston and extending through the cylinder, and a toggle connection between said outwardly-extending member and a stationary member carried by the cylinder, substantially as described.

11. A device of the character described comprising a rotating cylinder, a propeller carried therewith and composed of adjustable blades, a piston within the cylinder, a piston-rod carried by the piston, means carried by the piston-rod for adjusting the blades, an outwardly-extending member carried by the piston and extending through the cylinder, a toggle connection between said member and a stationary member carried by the cylinder, and a mechanism operated by the piston for throwing said toggle off of the center, substantially as described.

12. A device of the character described comprising a rotating cylinder, a propeller carried therewith and composed of adjustable blades, a piston within the cylinder, a piston-rod carried by said piston, means carried by the piston-rod for adjusting said blades, an outwardly-extending member carried by the piston, and extending through a slot in the cylinder, a toggle connection between said member and a stationary member carried by the cylinder, a key adapted to slide under said toggle connection and the cylinder, and means operated by the cylinder and the toggle, substantially as described.

13. A device of the character described comprising a rotating cylinder, a propeller carried therewith and composed of adjustable blades, a piston within the cylinder, a piston-rod carried by the piston, means operated by the piston-rod for adjusting said blades, a mechanism operated by the piston for locking said piston and means operated by the piston for releasing said locking mechanism, substantially as described.

14. A device of the character described comprising a rotating cylinder, a propeller carried therewith and composed of adjustable blades, a piston within the cylinder, a piston-rod carried by the piston, means carried by the piston-rod for adjusting said blades, a movable member surrounding the cylinder, means carried by the piston for operating said member, and means operated by said member for locking said piston, substantially as described.

15. A device of the character described comprising a rotating cylinder, a propeller carried therewith and composed of adjustable blades, a piston within the cylinder, a piston-rod carried by the piston, means carried by the piston for operating the blades, a movable member surrounding the central portion of the cylinder, a key extending through the cylinder and piston and moving said movable member, stationary members carried by the ends of the cylinder, toggle connections between said stationary members and movable member, and means operated by the piston for releasing said toggle connections, substantially as described.

16. A device of the character described, comprising a rotary cylinder, a propeller carried therewith and composed of adjustable

- blades, a piston within the cylinder, a piston-rod carried by the piston, means operated by the piston for adjusting said blades, stationary steam-supply rings surrounding the cylinder adjacent its ends, and a combined steam and exhaust pipe connected with said rings, substantially as described.
17. A device of the character described comprising a rotary cylinder, a propeller carried therewith and composed of adjustable blades, a piston within the cylinder, a piston-rod carried by the piston, means operated by the piston-rod for adjusting the blades, a key passing through an elongated slot in the cylinder and a slot in the piston, toggle connections connected to said key and having opposite ends connected to the ends of the cylinder, outwardly-extending keys carried by the piston and having beveled outwardly-extending members, whereby the respective toggle is forced outwardly, substantially as described.
18. A device of the character described, comprising a rotating cylinder, a propeller carried therewith, and composed of adjustable blades, a piston within the cylinder, a piston-rod carried by the piston, means operated by the piston-rod for adjusting said blades, the said piston consisting of the parts, the two ends connected by bolts and a movable central portion slidable on said bolts, a movable member surrounding the central portion of said cylinder, a key carried by said member and passing through elongated slots in the cylinder and through the central movable portion of the piston, toggle connections carried by the outer sides of said movable member, the outer ends of said toggles connected to the ends of the cylinder, keys carried by the inner ends of the end sections of said piston and extending out through the elongated slots in the cylinder, and beveled members carried thereby and adapted to force the said toggle connections outwardly when the piston is moved, substantially as described.
19. A mechanism of the character described, comprising a propeller composed of adjustable blades, a rotatable cylinder carrying said propeller, a steam-operated piston within said cylinder and means operated by said piston for adjusting said blades, substantially as described.
20. A mechanism of the character described comprising a rotating cylinder, an outwardly-extending member carried by said cylinder and rotating therewith, laterally-extending adjustable blades carried by said member, outwardly-extending studs carried by said member, a block slidable on said studs, links connecting said block and blades, and a piston-rod connecting the said block and the piston, substantially as described.
21. A mechanism of the character described, comprising a rotating cylinder, a piston therein, an outwardly-extending member carried by said cylinder, laterally-extending studs carried by said member, propeller blades loosely mounted thereon, outwardly-extending studs carried by the end of said member, a block slidable on said studs, links connecting said block and blades, and a piston-rod connecting said block and piston, substantially as described.
22. A device of the character described, comprising a rotating cylinder, a propeller carried therewith and composed of adjustable blades, a piston within the cylinder, a piston-rod carried by the piston, means carried by the piston-rod for adjusting said blade, and toggle connections between said piston and a stationary member carried by the cylinder, substantially as described.
23. A device of the character described, comprising a rotating cylinder, a propeller carried therewith, and composed of adjustable blades, a piston within the cylinder, a piston-rod carried by the piston, means carried by the piston-rod for adjusting said blades, a toggle connection between said piston and a stationary member carried by the cylinder, and means operated by the piston for throwing said toggle off the center, substantially as described.
24. A device of the character described, comprising a rotating cylinder, a propeller carried therewith and composed of adjustable blades, a piston within the cylinder, a piston-rod carried by the piston, means carried by the piston-rod for adjusting said blades, a movable member surrounding the cylinder, means carried by the piston-rod for operating said member, means operated by said member for locking said piston, and means operated by said piston for unlocking said means, substantially as described.
25. A mechanism of the character described, comprising a propeller composed of adjustable blades, a rotatable cylinder carrying said propeller, a piston within said cylinder, a mechanism operated by said piston for adjusting said blades, means operated by the piston for locking said blades in the adjusted position, substantially as described.
26. A mechanism of the character described, comprising a propeller composed of adjustable blades, a rotatable cylinder carrying said propeller, a piston within said cylinder, a mechanism operated by said piston for adjusting said blades, means operated by the piston for locking said blades in said adjusted position and means operated by the piston for unlocking said locking means, substantially as described.
27. A mechanism of the character described, comprising a propeller composed of adjustable blades, a cylinder carrying said propeller, a piston within said cylinder, and means operated by the piston for adjusting said blades, substantially as described.
28. A mechanism of the character described, comprising a propeller composed of adjustable blades, a rotatable cylinder carrying said

propeller and having steam-inlets adjacent each end, stationary steam-supply rings surrounding said cylinder and covering said supply-inlets, a piston within the cylinder, and
5 means operated by the piston for adjusting said blades, substantially as described.

In testimony whereof I have hereunto set

my hand in the presence of two subscribing witnesses.

GEORGE L. McCALLUM.
